CLAIM

The ornamental design for a vehicle compartment lock, as shown and described.

DESCRIPTION

FIG. 1 is a front elevational view of a vehicle compartment lock showing our new design;

FIG. 2 is a right side elevational view thereof;

FIG. 3 is a right side elevational view thereof;

FIG. 4 is a top plan view thereof;

FIG. 5 is a bottom plan view thereof;

FIG. 6 is a rear elevational view thereof; and,

FIG. 7 is a perspective view thereof.

The portions of the lock shown in broken lines in the drawings are for illustrative purposes only and do not form part of the claimed design.
